CLAIM

The ornamental design for a portion of an equipment console, as shown and described.

DESCRIPTION

FIG. 1 is a perspective of a portion of an equipment console of a first embodiment of the present invention;

FIG. 2 is a perspective of a portion of an equipment console of a second embodiment of the present invention; and,

FIG. 3 is a perspective of a portion of an equipment console of a third embodiment of the present invention.

The broken lines in the drawings indicate environmental structure and portions of the equipment console forming no part of the design. The bottom of the equipment console forms no part of the design.
